UNITED STATES PATENT OFFICE

2,573,975

TONE GENERATOR

Carl W. Larson, Minneapolis, Minn., assignor to
 Patent Management, Incorporated, Minneapolis, Minn., a corporation of Minnesota

Application August 1, 1950, Serial No. 176,942

4 Claims. (Cl. 171—209)

1

The herein disclosed invention relates to tone generators of the magnetic type for electric organs and has for an object to provide a tone generator in which a closed magnetic circuit is used.

Another object of the invention resides in providing a tone generator in which a toothed wheel and a smooth wheel are employed which are disposed adjacent one another in flux conducting relation.

A still further object of the invention resides in providing a tone generator in which a magnetic core is employed having two spaced legs formed with poles at the ends of the same arranged in flux conducting relation with respect to said wheels.

Another object of the invention resides in providing a permanent magnet between said legs at the other ends of the same and in further providing a coil on one of said legs.

A feature of the invention resides in providing a case for the core open at the rear and containing said coil and magnet and in further utilizing one of said legs as a closure for the rear of the case.

Another object of the invention resides in providing a support disposed adjacent said wheels and having a surface at right angles to the axis of said wheels and in further providing a U-shaped guide for said case open at its ends arranged on said surface with the direction of extent of said guide being radial and in which the case may be slid radially to vary the lengths of the air gaps between said poles and wheels.

Other objects of the invention reside in the novel combination and arrangement of parts and in the details of construction disclosed in this application.

In the drawings:

Fig. 1 is an elevational view of a portion of an electric organ with an embodiment of the invention applied thereto and drawn to an enlarged scale.

Fig. 2 is a cross sectional view taken on line 2—2 of Fig. 1.

Fig. 3 is an elevational sectional view taken on line 3—3 of Fig. 1.

Fig. 4 is an elevational view of the case and magnet with the spacer and rear leg of the core removed.

Fig. 5 is an elevational view of the rear leg of the core.

Fig. 6 is an elevational view of the spacer for the core.

The structure disclosed in this application for

2

patent consists of a plate serving as a support and through which a shaft extends. On this shaft is mounted a toothed wheel and a smooth wheel in flux conducting relation with respect to one another. A guide U-shaped in form and open at its ends is attached to the plate with the direction of its extent being radially with respect to said wheels. A case is slidably received in the guide and is itself U-shaped in form having side walls and a front wall. Partitions extending across the ends of the case close the ends of the same while an intermediate partition divides the interior of the case into two compartments. The case carries a core having a leg which extends through all three partitions, intermediate said walls and having one end projecting outwardly beyond the adjacent partition and formed with a pole adapted to be disposed adjacent the toothed wheel. The core has another leg which forms a closure for the rear of the case and which is also formed with a projecting end having a pole disposed adjacent the smooth wheel. Between the other ends of said legs is disposed a permanent magnet situated in one of said compartments while in the other compartment is a coil encircling said first named leg. A spacer disposed upon the exterior of said closure separates the same from said plate. Adjustment of the case along said guide varies the length of the air gap between said poles and wheels.

For the purpose of illustrating the invention a support 10 has been shown which is in the form of a plate and which constitutes a part of an electric organ used to support the magnet units of the tone generators of the organ. This plate has a hole 11 in the same and through which a shaft 12 extends. This shaft is of non-magnetic material such as brass, bronze or certain types of stainless steel and is journalled in bearings not shown and which are mounted on supporting structure with reference to which the plate 10 is fixed. The axis of the shaft 12 is at right angles to the surface 13 of plate 10.

On the side of the surface 13 of plate 10 are mounted on shaft 12, a wheel 14 having a smooth circumferential face 15, and a wheel 16 having a number of teeth 17 equally spaced and disposed at the periphery of said wheel. The wheels 14 and 16 are constructed of iron, steel or some other suitable flux conducting material and are arranged close to one another so as to be in magnetic flux conducting relation. Collars 18 and 19 on said shaft 12 hold the wheels 14 and 16 in proper position on said shaft with relation to

the plate 10 and other parts on the shaft. These collars are also of material similar to shaft 12.

Cooperating with the wheels 14 and 16 is a magnetic unit 20. This unit includes a case 21, U-shaped in form, which is preferably bent up from metal and which has a front wall 22 and side walls 23 and 24. Partitions 25 and 26 extend across the walls 22, 23, and 24 and close the ends of the case. An intermediate partition 27 also extends across the walls of the case and forms in it two compartments 28 and 29. All of the partitions are constructed of insulating material and are somewhat shorter than the widths of the walls 23 and 24.

The magnet unit 20 further comprises a core 30 which includes two spaced legs 31 and 32. The leg 31 is in the form of a bar and extends through all of the partitions 25, 27 and 26 intermediate the walls 22, 23 and 24 and the rear edges of the walls 23 and 24. This bar has one end extending outwardly beyond the partition 26 and constructed to form a pole 33 for cooperation with the teeth 17 of the wheel 16. On this leg is wound a coil 34 which is disposed in compartment 29. The other leg 32 of the core 30 is in the form of a plate and is shown in detail in Fig. 5. The width of this plate is equal to the distance between the walls 23 and 24 so that said plate fits in between said walls and rests on the partitions 25, 26 and 27. Ears 35 on said plate engage the ends of said walls and prevent longitudinal movement of the plate relative to the case. One end of the leg 32 projects outwardly beyond the partition 26 and is constructed to provide a pole 36 which is adapted to cooperate with the surface 15 of wheel 14. The other end of this plate has a lug 37 formed on the same which has a hole 38 in it. This construction may be used for a purpose to be presently described. A permanent magnet 42 is disposed between the two legs 31 and 32 at the ends thereof opposite the poles 33 and 36 and is disposed in the compartment 28 fitting snugly between the partitions 25 and 27. This magnet is polarized in the direction between the two legs and forms a yoke therebetween. This magnet, the partitions 25, 26 and 27, the leg 31 and coil 34 are all firmly cemented together and to the case 21. Ears 43 on the ends of wall 22 of case 21 extend over the partitions 25 and 26 and further assist in holding the parts assembled.

The magnet unit 20 is adjustably mounted in a guide 38 best shown in Figs. 1 and 2. This guide is constructed from sheet metal and is U-shaped in form having a front wall 40, and side walls 41 and 42, being open at the top, bottom and the back. Flanges 44 and 45 extend outwardly from the walls 41 and 42 and are adapted to overlie the surface 13 of plate 10. The flange 44 is secured to the plate 10 by means of rivets 46 while the flange 45 may be clamped up against the said plate by means of a screw 47 passing through said flange and screwed into said plate. The entire magnet unit 20 is adapted to be received in the guide 38 with the walls 22, 23 and 24 disposed adjacent the walls 40, 41 and 42 a spacer 48 best shown in Figs. 3 and 6 is disposed between the leg 32 and the surface 13 of plate 10. This spacer is of the exact form of the leg 32 except that it does not have a pole or lug but does have ears 49 similar to the ears 35. This spacer is received between the walls 23 and 24 of the case 21 and said ears 49 engage the ends of said walls. With the unit

30 properly installed in the guide 38, pole 33 is in the path of movement of the teeth 17 of wheel 16 and pole 36 lies opposite the surface 15 of wheel 14. By sliding the unit along said guide through engagement with lug 37 the length of the air gaps between the poles and wheels may be adjusted as desired. When the unit is properly adjusted tightening of screw 47 holds the parts in proper position.

If desired several magnet units may be employed cooperating with a single pair of wheels. Where they are desired in pairs another guide 59 would be used which is similar to the guide 38. In such case the flange 51 of said guide may be integral with the flange 44 of guide 38 and only one set of rivets used for both guides.

The use of the invention is obvious. The magnet units may be adjusted by loosening screw 47 and sliding the unit along the guide 38. Tightening the screw locks the parts together and also clamps the legs 31 and 32 against the magnet 42.

The invention has numerous advantages. The device is extremely simple and is positive in action. With the closed magnetic circuit less amplification is required and better tone quality results. The units can be constructed at a nominal expense, and are compact in size. The units are readily replaceable and adjustable to procure different length air gaps and the attendant advantages thereof.

What is claimed to be new and desired to be protected by Letters Patent is:

1. In a tone generator, a toothed wheel and a smooth wheel disposed in magnetic flux conducting relation adjacent each other and mounted on a revolvable shaft, a U-shaped case open at the back and at its ends and having side walls and a front wall, partitions at the ends of the case closing the ends of the same, a partition intermediate said first named partitions and extending across the case and dividing the same into two compartments, a magnetic core including a leg extending through one of said first named partitions and through said intermediate partition and spaced from the walls of the case, said core having a second leg disposed at the rear of the case and forming a rear wall for the case, poles on corresponding ends of the legs of the core and projecting outwardly beyond the portion adjacent such ends of the legs, means for supporting said poles in flux conducting relation with respect to said wheels, a permanent magnet disposed between the other ends of the legs and disposed in the compartment in which said ends of the legs are situated, and a coil wound on said first named leg and disposed in the other compartment and energized by variation in flux passing through the air gaps between said poles and wheels and produced by rotation of said shaft.

2. In a tone generator, a toothed wheel and a smooth wheel disposed in magnetic flux conducting relation adjacent each other and mounted on a revolvable shaft, a plate forming a support and disposed at right angles to said shaft and adjacent one of said wheels, a U-shaped guide open at its ends and attached to said plate, with the longitudinal direction of extent of said guide being disposed in a radial direction with reference to said wheels, a case insertable into said guide and slideable along the same in a radial direction, a magnet carried by said case and having two legs extending in a radial direction, poles on the ends of said legs

and adapted to be disposed, one in flux conducting relation with said toothed wheel and the other in flux conducting relation with said smooth wheel, and a coil on one of said legs, the air gaps between said poles and wheels being variable by moving said case along said guide.

3. In a tone generator, a toothed wheel and a smooth wheel disposed in magnetic flux conducting relation adjacent each other and mounted on a revolvable shaft, a plate forming a support and disposed at right angles to said shaft and adjacent one of said wheels, a U-shaped guide open at its ends and attached to said plate, with the longitudinal direction of extent of said guide being disposed in a radial direction with reference to said wheels, a case U-shaped in form having a front wall and side walls and insertable into said guide through the open end thereof and slideable along said guide, partitions at the end of the case, extending across said walls, a magnetic core including a leg extending through one of said partitions intermediate said walls, a closure for the rear of said case and forming another leg of said core and projecting outwardly beyond said case at the same end as first named leg, poles on the projecting ends of said legs and disposed in flux conducting relation with said wheels and a spacer between said last named leg and said plate.

4. In a tone generator a toothed wheel and a

smooth wheel disposed in magnetic flux conducting relation adjacent each other and mounted on a revolvable shaft, a supporting plate, a U-shaped guide having a front wall, side walls and flanges extending outwardly from said side walls and overlying said plate, screws extending through said flanges and engaging said plate to hold the guide attached to the plate, a case disposed within said guide, a magnet carried by said case and having legs extending outwardly therefrom and formed with poles, means for holding said wheels in flux conducting position with reference to said poles, said guide guiding said case and magnet for movement toward and from said wheels, said screws serving to draw said flanges toward said plate and to clamp the case in position between said front wall of the case and the plate.
